UNITED STATES PATENT OFFICE.

WALTER C. SCHNEIDER, OF DETROIT, MICHIGAN.

CARBURETER.

No. 868,707.

Specification of Letters Patent.

Patented Oct. 22, 1907.

Application filed February 26, 1907. Serial No. 359,232.

To all whom it may concern:

Be it known that I, WALTER C. SCHNEIDER, a citizen of the United States, residing at Detroit, in the county of Wayne and State of Michigan, have invented certain new and useful Improvements in Carbureters, of which the following is a specification.

The object of my invention is to provide an improved carbureter, the same being especially designed for employment in connection with internal combustion engines, and it consists of the construction, combination and arrangement of devices hereinafter described and claimed and illustrated in the accompanying drawings, in which,

Figure 1 is a view in side elevation. Fig. 2 is a view in vertical section. Fig. 3 is a plan view. Fig. 4 is a horizontal section on the line 4—4, Fig. 1. Fig. 5 is a detail view of the throttle valve.

The aim of my present invention is to provide a carbureter of superior efficiency and utility, and one in which the feed shall be governed automatically.

I carry out my invention as follows:

In the drawings *a* represents any suitable case or body forming a carbureting chamber *b* provided with a discharge pipe *c*, the discharge being controlled by a throttle valve indicated at *d*. Within the carbureting chamber is located a hub indicated at *e* forming a valve seat at its upper end as shown at *f*, the hub being channeled as indicated at *g* and communicating with a feed channel *h* into which a feed pipe *i* leads from any suitable source of supply. The base of the case *a*, to this end, may be formed with a cross arm *j*, the lower end of the case being open to receive an air supply. About the upper end of the hub *e* I locate a rotatable fan indicated at *k*, the fan being mounted upon the hub by intervening ball bearings of any suitable construction indicated at *l*. Above the ball bearing I locate a deflecting cone *m*. A valve *n* seats upon the valve seat *f* provided with an operating lever *p*, the valve stem preferably having a threaded engagement in the cap *q* of the case as indicated at *r*.

In operation when the valve *n* is open the fuel supply feeds through the channel *g* overflowing upon the cone *m* and thereby being distributed upon the rotatable fan *k*, the fan being rotated by the suction in the carbureting chamber whereby, it will be obvious, the

liquid hydrocarbon is given a centrifugal impulse to effectually spray or vaporize the liquid hydrocarbon. The vaporized hydrocarbon mixed with air is discharged to the engine. It will readily be seen that when the engine is running at high speed, the suction will be greater than when running at low speed, so that the feed supply passing through the carbureter will be effectually governed thereby in proportion to the speed at which the engine is running. The throttle valve *d* may be actuated in any suitable manner but as shown the same may be provided with upwardly projecting lugs indicated at *s*, *s* between which the throttle lever *p* extends so that the same lever will operate both of the valves named simultaneously. The valve *n* may be regulated as desired by means of the threaded engagement of its stem with the cap *q* and then, it will be observed that by means of the throttle lever the discharge opening and the opening of the valve *n* will be proportional the one to the other.

What I claim as my invention is:

1. A carbureter comprising a carbureting chamber, a channeled hub within said chamber, a feed inlet passage opening leading into the channel of the hub, a manually operated valve to control said channel, and a rotatable fan supported upon said hub below the valve.

2. A carbureter, comprising a carbureting chamber provided with a feed inlet and a discharge outlet, a channeled hub within the said chamber communicating with the feed inlet and forming a valve seat at the upper end thereof, a manually operated valve to seat upon said valve seat, and a rotatable fan supported upon said hub below the valve seat, substantially as described.

3. A carbureter, comprising a carbureting chamber, a feed inlet passage opening into said chamber, a channeled hub within said chamber, a valve to control the channel of the hub, a rotatable fan supported upon the hub below said valve, and a deflecting cone above the fan.

4. A carbureter, comprising a carbureting chamber, a feed inlet passage opening into said chamber, a discharge passage leading therefrom, a channeled hub within said chamber, a valve to control the channel of the hub, a rotatable fan supported upon the hub below said valve, a valve to control the outlet passage, and a lever to simultaneously actuate both of said valves.

In testimony whereof I affix my signature in presence of two witnesses.

WALTER C. SCHNEIDER.
